(57) **CLAIM**

The ornamental design for a temperature monitor, as shown and described.

DESCRIPTION

FIG. 1 is a perspective view of the temperature monitor of this invention.

FIG. 2 is a top plan view of the temperature monitor shown in FIG. 1.

FIG. 3 is a left side elevational view of the temperature monitor shown in FIG. 1.

FIG. 4 is a lower end elevational view of the temperature monitor shown in FIG. 1.

FIG. 5 is a bottom plan view of the temperature monitor shown in FIG. 1.

FIG. 6 is a right side elevational view of the temperature monitor shown in FIG. 1; and,

FIG. 7 is an upper end elevational view of the temperature monitor shown in FIG. 1.
